JETELEVATOR SYSTEM DESIGN

Fredrick R. Barnet, Kensington, Md., assignor to the United States of America as represented by the Secretary of the Navy

Filed Mar. 9, 1960, Ser. No. 13,967

3 Claims. (Cl. 60—35.55)

(Granted under Title 35, U.S. Code (1952), sec. 266)

The invention described herein may be manufactured and used by or for the Government of the United States of America for governmental purposes without the payment of any royalties thereon or therefor.

This invention relates to a sealing ring for application between an exhaust nozzle and a jetelevator.

Vector control on missiles may be obtained by the deflection of the exhaust gases at the nozzle termination by a jetelevator which is affixed to the nozzle. The present high energy propellants contain large quantities of aluminum. This is present in the exhaust gases either as vapor or a highly dispersed liquid, and many times is deposited on the inner surface of the jetelevator so as to interfere with its operation. This depositing occurs because the jetelevator acts as a heat sink and the alumina is condensed and adheres to the inner surface of the jetelevator. This adherence is sometimes sufficient to interfere with the operation and render the jetelevator inoperative.

It is an object of the present invention to provide a seal attached to the nozzle and in contact with the jetelevator to prevent the deposition of alumina in sufficient amounts so as to interfere with the operation.

It is another object to provide a graphite ring seal at the end of the nozzle and in contact with the inner surface of the jetelevator to wipe the inner surface of the jetelevator and coat said surface with a film of graphite to prevent the adherence of the particles of alumina in the exhaust gases to the inner surface of the jetelevator.

It is a further object of the invention to provide a graphite annular seal at the exhaust end of the nozzle and to secure the seal to the nozzle by an adhesive and by mechanical means.

It is a still further object of the invention to provide a seal between the nozzle and the jetelevator which would lubricate the inner surface of the jetelevator during its operation and in case of alumina deposits on the inner surface of the jetelevator the graphite seal would not provide a stop to prevent the operation of the jetelevator but would receive the alumina particles into its comparative softer surface.

Other objects and many of the attendant advantages of this invention will be readily appreciated as the same becomes better understood by reference to the following detailed description when considered in connection with the accompanying drawing wherein:

FIG. 1 is a longitudinal section of a nozzle with attached seal and jetelevator;

FIG. 2 is a similar view with the jetelevator in a different position; and

FIG. 3 is a similar view showing how the alumina particles score the graphite seal to permit lubrication.

Referring to the drawing wherein like numerals designate like parts in the several figures, a nozzle 11 for a missile is illustrated having a bore 12 restricted at 13 and gradually enlarged to the exhaust end 14. The nozzle has its exterior surface spherical shaped at 16 to receive the jetelevator 17. A pair of pins (not shown) extend from diametrical opposite points of the spherical portion and support the jetelevator for limited oscillatory movement controlled by levers or gears (also not shown).

The jetelevator at its outer opening is recessed at 18.

2

Ordinarily the outer portion is spaced from the nozzle by approximately $\frac{1}{8}$ inch and the alumina deposits sometimes fill this space.

The exhaust end of the nozzle is recessed at 21 to receive the annular base 22 of a graphite sealing ring 23. The sealing ring is secured to the nozzle by adhesive between the metal surface of the nozzle and the graphite surface of the ring. Screws 24 threaded into holes 25 also hold the ring in position. The sealing ring extends into the recess 18 and is in sealing contact with the jetelevator. The inner surface of the sealing ring is an extension of the inner surface of the nozzle and presents no obstruction to the flow of exhaust gases. The graphite ring serves as a seal, a bearing and a lubricant for the jetelevator. It extends beyond the nozzle and into close contact with the jetelevator thus preventing turbulence of exhaust gases formerly caused by the clearance between the nozzle and the jetelevator.

FIG. 2 illustrates the position of the jetelevator when it is used to change the direction of flight of the missile, the exhaust gases being deflected by the inner surface 27 of the jetelevator. The movement of the jetelevator in moving from the position shown in FIG. 1 to that shown in FIG. 2 causes the inner surface 27 of the jetelevator to wipe the graphite surface of the seal resulting in a deposit of graphite on the inner face 27. This deposit of graphite will inhibit the deposition of alumina on the inner surface 27 and the closely spaced relationship of the jetelevator and the graphite seal insures against the accumulation of alumina particles between the nozzle and the jetelevator.

Should the coating of graphite on the inner surface 27 be not complete and some particles of alumina are deposited, the soft surface of the graphite seal will be scored, as seen in FIG. 3 to permit the jetelevator to function.

The close adherence of the seal to the jetelevator also keeps the exhaust gases out of contact with the inner surface of the jetelevator where they were formerly directed by the inner surface 27 by reason of the clearance between the jetelevator and the nozzle and prevents the overheating of the jetelevator in those bearing surfaces 28 which contact the spherical surface 16 of the nozzle. This assists in maintaining the jetelevator in operative condition as uneven expansion of these bearing surfaces can cause binding.

Obviously many modifications and variations of the present invention are possible in the light of the above teachings. It is therefore to be understood, that within the scope of the appended claims, the invention may be practiced otherwise than as specifically described.

What is claimed and desired to be secured by Letters Patent of the United States is:

1. An exhaust nozzle for a missile comprising a body portion having a tapered bore terminating in a nozzle opening, an exterior spherical bearing surface formed at the end of the body portion, a jetelevator mounted on said bearing surface for limited movement, means for moving said jetelevator relative to the body portion, a graphite seal mounted on the body portion and forming the nozzle opening, said seal being in contact with the inner surface of the jetelevator whereby movement of the jetelevator to operative position coats the inner face of the jetelevator, which after movement is exposed to the exhaust gases with a coating of graphite.

2. An exhaust nozzle for a missile comprising a body portion having a tapered bore terminating in a nozzle opening, said body portion having an exterior spherical surface adjacent said opening, an annular graphite seal secured to the end of the body portion, the inner surface of said seal conforming to and forming part of the tapered

bore, the outer surface of said seal being concentric with the spherical surface of said body portion, a jetevator mounted for universal movement on the spherical surfaces of said body portion and said seal, movement of said jetevator on said spherical surfaces coating a portion of the inner surface of said jetevator with graphite.

3. A nozzle according to claim 2 wherein the spherical surface of the graphite seal is of greater diameter than the spherical surface of the body portion, to shield the bearing surface of the body portion from the exhaust gases.
